UNITED STATES PATENT OFFICE

ANDREW FLORY, OF CLIFFSIDE PARK, NEW JERSEY, ASSIGNOR TO DUPLEX SILK CORPORATION, OF NEW YORK, N. Y., A CORPORATION OF DELAWARE

DESIGN FOR A TEXTILE FABRIC

Application filed July 7, 1930. Serial No. 36,291. Term of patent 3½ years.

To all whom it may concern:

Be it known that I, ANDREW FLORY, a citizen of the United States, residing at 18 Cortland Place, Cliffside Park, county of Bergen, State of New Jersey, whose post-office address is 132 Madison Avenue, borough of Manhattan, city of New York, county of New York, and State of New York, have invented a new, original, and ornamental Design for a Textile Fabric, of which the following is a specification, reference being had to the accompanying drawing, forming part thereof.

The figure is a plan view of a textile fabric showing my new design.

A single unit of my design is substantially comprised within the area defined by the indicating lines shown on the drawing, which unit is repeated over the surface of the fabric in the relation indicated.

I claim:

The ornamental design for a textile fabric substantially as shown and described.

ANDREW FLORY.
